DESIGN FOR A COMBINED BATTERY CHARGER AND TESTER

Charles G. Sherman and William P. Ryan,
Kansas City, Mo., assignors to C. Earl Hovey,
Kansas City, Mo., as trustee

Application December 2, 1941, Serial No. 104,439

Term of patent 7 years

To all whom it may concern:

Be it known that we, Charles G. Sherman and William P. Ryan, citizens of the United States, both residing at Kansas City, in the county of Jackson and State of Missouri, have invented a new, original, and ornamental Design for a Combined Battery Charger and Tester, of which the following is a specification, reference being had to the accompanying drawing, forming a part thereof.

Fig. 1 is a perspective view of the combined

battery charger and tester, showing our new design.

Fig. 2 is a side elevational view thereof; and Fig. 3 is a top plan view thereof.

The rear of the battery charger and tester is substantially plain and without ornamentation.

We claim:

The ornamental design for a combined battery charger and tester, as shown and described.

CHARLES G. SHERMAN.
WILLIAM P. RYAN.
